UNITED STATES PATENT OFFICE.

GEORGE D. WINCHELL, OF CINCINNATI, OHIO.

DESIGN FOR A TOILET-VESSEL.

SPECIFICATION forming part of Design No. 13,689, dated February 27, 1883.

Application filed January 22, 1883. Term of patent 3½ years.

To all whom it may concern:

Be it known that I, GEORGE D. WINCHELL, a citizen of the United States, residing at Cincinnati, in the county of Hamilton and State 5 of Ohio, have invented a new and ornamental Design for a Toilet-Vessel, of which the following is a specification, reference being had therein to the accompanying drawing.

My design is clearly shown in the annexed 10 illustration, which is a perspective view of the vessel.

A represents the base, from which the various sides, B, swell outwardly, then curve inwardly near the center, and finally bow outwardly at top, where said sides join the marginal flange or rim C. Consequently the 15 sides are approximately of an ogee shape in vertical section, and are so mitered together at their junctions as to form an octagonal vessel or tub of any convenient size. Furthermore, the exterior of sides B are preferably 20 painted to imitate panels, which panels may be surrounded with suitable borders, the panels themselves inclosing pictures of flowers,

fruit, or other desired ornaments. The handles D may either be plain or ornamental, to suit the demands of the trade. This vessel is one of three members of a toilet set that includes a foot-tub, water-carrier, and slop-jar, embodying the same design, the only difference being that the carrier and jar are somewhat higher in proportion to their diameters than the vessel herein illustrated.

I claim as my invention—

The design for a toilet-vessel, as herein shown 25 and described, which design includes an octagonal receptacle having a base, A, and marginal flange C, united by the sides B, said sides being bowed outwardly, then inwardly, and again outwardly, where they join said 30 flange.

In testimony whereof I affix my signature in presence of two witnesses.

GEORGE D. WINCHELL.
